UNITED STATES PATENT OFFICE

2,454,400

AUTOMATIC STOKER

Joseph T. Norman, Huntington Mills, Pa.

Application February 28, 1945, Serial No. 580,149

9 Claims. (Cl. 110—29)

1

My invention relates to self-stoking furnaces and it particularly relates to the mechanism for delivering and feeding the fuel to the fire as needed and causing discharge of the ash and clinkers under pressure.

An object of my present invention is to provide a stoker which will burn any and all usual sizes of coal and also will burn wood in logs or other shapes.

Again it is an object to provide a self-stoking furnace that, especially when coal is the fuel used, will operate on natural draft, although I prefer to use a suction blower or fan in the connection between the furnace and the chimney and control the same and the stoking motor by use of any of the known thermostat regulators.

Other objects will in part be obvious and in part be pointed out hereinafter.

To the attainment of the aforesaid objects and ends the invention further resides in those novel details of construction, combination and arrangement of parts all of which will be first fully described and then be specifically pointed out in the appended claims, reference being had to the accompanying drawings in which:

Fig. 1 is a vertical cross section of one embodiment of my invention, taken on the line 1—1 of Fig. 2.

Fig. 2 is a front elevation on a reduced scale of the structure shown in Fig. 1.

Fig. 3 is a view similar to Fig. 1 showing a second embodiment of my invention.

Fig. 4 is a vertical section, on a reduced scale, on the line 4—4 of Fig. 3.

Fig. 5 is a view similar to Fig. 1 showing the invention adapted to a hot air furnace.

In the drawings in which like numerals and letters of reference indicate like parts in all the figures, 1 indicates the shell or housing of the heating chamber H, and 2 indicates the bottom thereof. The shell 1 is provided with outlets 3 to which the hot water conduits to the radiators (not shown) are coupled, the return flow conduits (not shown) being connected to inlet nipples 49.

Passing through the front wall and the bottom of the shell 1 is an arcuate (preferably about semi-circular in vertical section) fire box 4, the entrance to which is at the top and the exit end of which is at the bottom. The cross-sectional area of the fire box, preferably, progressively increases from the entrant to the exit end. The fire box 4 has flue outlets 5 for smoke and other products of combustion, from which outlets ducts 6 extend upwardly to a header 7 from which a pipe 8 passes through the top of the shell 1 and

connects to the chimney, preferably via a suction blower or fan, not shown. The header 7 has clean-out doors 7^x. The fire box 4 has an opening 9 normally closed by a suitable door 9^x (see Figs. 1 and 4), through which the fire may be lighted.

At the lower end of the fire box is an approximately vertically disposed hinged grate 10 which is either weight-loaded as in Fig. 1 or it may be spring loaded as in Fig. 3.

10 A spiral rotary grate 11 is disposed at the bottom of the fire box adjacent the grate 10 and is slowly turned by means of a pawl 16 and ratchet 14, the pawl 16 being carried by a rocking lever 15 pivoted on the shaft 13 of the grate 11 and operated by a crank disc 24 and connecting rod 25. A backing grate 12 is located behind the rotary grate. The rotary grate may be dispensed with if desired (see Fig. 3 for instance).

The crank disc 24 is carried on a stub shaft 21 journaled in a bearing 22 (see Fig. 2), and driven by a sprocket and chain connection 23 to the electric motor M that is mounted on the shelf 48.

The motor M also drives via a sprocket and chain connection 20, a shaft 17 mounted in bearings 18 and carrying two crank discs 19 to which connecting rods 30 are pivoted, the rods 30 also being pivoted to brackets 29 on a carriage 27 whose wheels 28 run in tracks 26 formed of channel irons. The carriage 27 has slots 31 in its front end 32 through which the arms 33^x of a U-shaped spring loaded pusher 33 slide. Stops 34 prevent the springs 35 from pushing out the member 33 too far. A plate 36 lies beneath the pusher so that when the carriage is retracted fuel will drop, through the throat 37^x of the hopper 37, in front of the pusher 33.

A suitable draft regulator 38 admits air into the ash pit A to be drawn up through the fire bed to support combustion and a suitable clean-out 47 for the ash pit A is also provided.

When wood is the fuel used the logs, properly cut to lengths, are placed in the hopper 37 as indicated at W in Fig. 1 and are forced down 45 into the fire box 4 by the reciprocations of the carriage 27. If when the furnace is operating fuel is not required to be pushed along the pusher 33 will yield owing to the spring 35 and thus not feed more than the required amounts depending 50 on the rate of combustion and discharge of ashes.

The embodiment of Figs. 1 and 2 just described can be used to burn either wood or coal, and be either a hot water or steam boiler (hot water boiler being shown).

55 The embodiment of Figs. 3 and 4 is used for

burning coal principally, although, it can also be used to burn comminuted wood or wood in small enough pieces to compare with coal sizes. In these figures the boiler is shown as a steam boiler.

In Figs. 3 and 4 those parts which correspond to and are substantially the same as like parts in Figs. 1 and 2 bear the same reference number or letter plus the index letter *a*. In this embodiment of my invention the upper end of the fire box 4a communicates with a worm housing 46 (which may be formed integrally with the fire box walls) in which is a worm 41 that feeds the fuel the full length of the furnace. The worm 41 has a shaft 42 and may be of substantially the same construction as the worm 18 of my Patent #2,355,101 issued August 8, 1944.

In the embodiment of Fig. 3 the rotary grate is dispensed with and only a hinged, vertical grate 10a is used. This grate 10a is mounted on a wall 44 which also has a bearing through which a rod 46 passes. One end of this rod is secured to the grate 10a and the other end is spring-loaded, as at 45.

A motor M^a drives the worm 41 via a belt and pulley or sprocket and chain drive 43. The hopper 39 delivers the coal C to one end of the worm 41.

The worm carries the coal across the furnace and delivers it into the entrant end of the fire box with sufficient force to force the fuel and ashes down the curved way and effect discharge of the ashes as indicated in Fig. 3.

In Fig. 3 a water level gage 50 is employed.

When the invention is applied to a hot air furnace an air inlet 51 is provided in which a fan 52 is located to force air into the furnace as shown in Fig. 5. In this figure those parts which correspond to like parts in the preceding figures bear the same reference number plus the index letter *b*.

It will be noted that in all embodiments of my invention the fire box 4 is of gradually increasing cross-sectional area from the top or entrant end to the bottom or exit end. This prevents choking the passage by fuel and ash.

The action of the motors M, M^a and M^b may be controlled by any suitable thermostatic heat regulator but as the same is not part of my invention, I have not disclosed same in this specification and the accompanying drawings. Also any suitable speed reducer (not shown) may be used with the motors.

From the foregoing description taken in connection with the accompanying drawings it is thought the construction, operation and advantages of the invention will be clear to those skilled in the art.

What I claim is:

1. A furnace having a shell enclosing a heating chamber and a fire box, said fire box being fixedly held and having an entrance at one side of the shell and extending inwardly therefrom and curved downwardly, said fire box at a location between its ends having flue openings; ducts within the heating chamber and connected to said fire box at each flue opening; a header within said heating chamber into which said ducts deliver products of combustion and an off-take duct from the header to the outside of the heating chamber; an upright grate at the outlet end of said fire box, means for forcing fuel into and along said fire box and expelling ashes from the same, and means to admit air to the exit end of said fire box for combustion purposes.

2. A furnace having a shell enclosing a heat-

ing chamber and a fire box, said fire box being fixedly held and having an entrance at one side of the shell and extending inwardly therefrom and curved downwardly, said fire box at a location between its ends having flue openings; ducts within the heating chamber and connected to said fire box at each flue opening; a header within said heating chamber into which said ducts deliver products of combustion and an off-take duct from the header to the outside of the heating chamber; an upright grate at the outlet end of said fire box, means for forcing fuel into and along said fire box and expelling ashes from the same, and means to admit air to the exit end of said fire box for combustion purposes, said fuel forcing means comprising a fuel hopper and means for taking fuel from the hopper and forcing it into the top end of the fire box.

3. In self-stoking furnace: the improvement which includes a shell enclosing a fluid chamber and a heating chamber within which heating chamber is a fixedly held fire box composed of an approximately semi-circular duct having at least one flue opening intermediate its entrant and exit ends, a duct from said flue opening through said heating chamber to the outside of the same, means for intermittently forcing fuel into the entrant end of and through said fire box duct and forcing the ashes from the exit end of the fire box duct, a vertical grate at the exit end of the fire box, means for admitting air for combustion to the fuel in the fire box, and a heating fluid offtake duct from said shell.

4. In a self-stoking furnace the improvement which comprises a fixedly held vertically disposed semi-circular duct fire box having both its entrant end and its exit end disposed at the same side of the furnace with the entrant end uppermost, said fire box intermediate its ends having at least one flue opening, a duct from said opening for the escape of products of combustion, means for forcing fuel through said fire box from its entrant end toward its exit end and past said flue, and a vertical grate and a rotary grate means at the exit end of said fire box.

5. In a self-stoking furnace the improvement which comprises a fixedly held vertically disposed semi-circular duct fire box having both its entrant end and its exit end disposed at the same side of the furnace with the entrant end uppermost, said fire box intermediate its ends having at least one flue opening, a duct from said opening for the escape of products of combustion, means for forcing fuel through said fire box from its entrant end toward its exit end and past said flue, rotary grate means at the exit end of said fire box, and means for admitting air to the grate end of said fire box for combustion purposes.

6. In a self-stoking furnace the improvement which comprises a fixedly held vertically disposed semi-circular duct fire box having both its entrant end and its exit end disposed at the same side of the furnace with the entrant end uppermost, said fire box intermediate its ends having at least one flue opening, a duct from said opening for the escape of products of combustion, means for forcing fuel through said fire box from its entrant end toward its exit end and past said flue, grate means at the exit end of said fire box, and means for admitting air to the grate end of said fire box for combustion purposes, said grate means comprising a pivoted vertically disposed bar-grate, a rotary grate adjacent to said bar-grate and a fixed bar-grate adjacent said rotary grate on the side opposite said pivoted bar-grate.

7. In a self-stoking furnace: the improvement which includes a shell enclosing a heating chamber within which is a fixedly held fire box composed of an approximately semi-circular duct having at least one flue opening intermediate its entrant and exit ends, a duct from said flue opening through said heating chamber to the outside of the same, means for intermittently forcing fuel into the entrant end of and through said fire box duct and forcing the ashes from the exit end of the fire box duct, a grate at the exit end of the fire box, means for admitting air for combustion to the fuel in the fire box, said shell having an outlet adjacent its top for connection to heat ducts and having an air inlet adjacent its bottom, and means for blowing air into said shell through said air inlet.

8. A furnace having a shell enclosing a heating chamber, an ash receiving chamber, and a semi-circular fire box having an entrant end at one side of said shell and an exit end adjacent and directed toward the same side of the shell as that in which the entrant end is located, said fire box at a suitable location between its ends having flue openings; ducts within said shell connected to said fire box in register with said flue openings; an offtake flue for said ducts to the outside of the casing; means for positively creating a suction in said offtake flue; a grate at the outlet end of said fire box; a fuel hopper; and means for conducting fuel from said fuel hopper to the entrant end of said fire box and forcing the fuel past said flue openings.

9. A furnace having a shell enclosing a heating chamber, an ash receiving chamber, and a semi-circular fire box having an entrant end at one side of said shell and an exit end adjacent and directed

toward the same side of the shell as that in which the entrant end is located, said fire box at a suitable location between its ends having flue openings; ducts within said shell connected to said fire box in register with said flue openings; an offtake flue for said ducts to the outside of the casing; means for positively creating a suction in said offtake flue; a grate at the outlet end of said fire box; a fuel hopper; and means for forcibly feeding fuel from said fuel hopper into and through said fire box and simultaneously forcing the ashes out of the same.
